UNITED STATES PATENT OFFICE.

MARY F. F. WILSON, OF NEW ROCHELLE, NEW YORK.

DESIGN FOR A LAMP-SHADE.

59,800.

Specification for Design.

Patented Nov. 22, 1921.

Application filed March 31, 1920. Serial No. 457,524. Term of patent 14 years.

To all whom it may concern:

Be it known that I, MARY F. F. WILSON, a citizen of the United States, residing at New Rochelle, in the county of Westchester and State of New York, have invented a new, original, and ornamental Design for a Lamp-Shade, of which the following is a specification, reference being had to the accompanying drawing, forming part thereof, wherein is shown an elevation of my new design.

I claim:

The ornamental design for a lamp shade, as shown.

MARY F. F. WILSON.
